DESIGN FOR A FUR JACKET

Simon Etkin, New York, N. Y.

Application June 14, 1938, Serial No. 77,825

Term of patent 3½ years

To all whom it may concern:

Be it known that I, Simon Etkin, a citizen of the United States of America, residing in New York city, in the Borough of Manhattan, county and State of New York, have invented a new, original, and ornamental Design for a Fur Jacket, of which the following is a specification reference being had to the accompanying drawing, forming part thereof, wherein,

The characteristic feature of the design resides in the specific waistband in association with the particular ornamentation at the neck closure in combination with the specific jacket as shown.

I claim:

The ornamental design for a fur jacket, substantially as shown, and described.

SIMON ETKIN.
